UNITED STATES PATENT OFFICE.

FRANK J. KROBOTH, OF NEW YORK, N. Y.

DEVICE FOR REMOVING SNOW, ICE, AND SLEET FROM CHANNELS AND CHANNEL-RAILS OF UNDERGROUND RAILWAYS.

1,130,523.

Specification of Letters Patent.

Patented Mar. 2, 1915.

Application filed November 5, 1914. Serial No. 870,503.

To all whom it may concern:

Be it known that I, FRANK J. KROBOTH, a citizen of the United States, and a resident of the city of New York, borough of Manhattan, in the county and State of New York, have invented a new and Improved Device for Removing Snow, Ice, and Sleet from Channels and Channel-Rails of Underground Railways, of which the following is a full, clear, and exact description.

This invention relates to an improved appliance or apparatus adapted for use in connection with underground railway systems and the object thereof is to provide improved means for removing snow, ice and sleet from the channels and channel rails of said railway systems.

Ordinarily, in railway systems having the usual underground channels and channel rails from which electric current is transmitted to the motor trucks of the cars through the medium of the ordinary plow and connections leading therefrom, the channels will become clogged up with snow, ice and sleet and when such collection has reached a height above the ordinary rails the further operation of the system must come to a stop. The present invention is designed to overcome these difficulties and for this purpose a novel form of fitting is provided to be suspended from the truck of a car somewhat similar to the manner of suspending the usual plow, and said fitting is provided with a plurality of nozzles designed to eject steam in a blast against the channel rails, at the entrance slot of the channel and into the channel for effectively melting the snow, ice and sleet which may collect, thus providing an efficient means to maintain the channel in such condition that the operation of a railway system may continue without interruption during the worst of inclement weather. It is also to be understood that the device is to be applied to a railway car at the outer ends of the trucks so as to proceed in front of the conductor plow which operates in the channel and is especially adapted for use with a special or two-truck sweeper as distinguished from the ordinary single truck sweeper, so that the same can be provided with a suitable steam generator thereon to supply steam to the fitting for simultaneous or independent discharge from the nozzles into the slot of the channel or against the

opposed channel rails, without interfering with the operation of the sweeper, the usual snow plow or other devices which are designed to remove the snow from the tracks in order to secure proper traction for the wheels of the car.

With the above and other objects in view, the invention resides in the peculiar combination and arrangement of parts to be hereinafter more fully described, illustrated and claimed, it being also an object to provide a device which is simple in construction, durable and efficient in operation and not likely to get out of working order.

Reference is to be had to the accompanying drawings forming a part of this specification, in which similar characters of reference indicate corresponding parts in all the views and in which—

Figure 1 is a fragmentary elevation of a car partly in section, equipped with the improved device or apparatus and showing the manner in which the same operates with the elements of the underground electric railway system; Fig. 2 is a plan view thereof with the body of the car omitted; Fig. 3 is an enlarged sectional elevation of the fitting designed to operate in the channel slot for discharging the steam as specified; Fig. 4 is an enlarged horizontal sectional view through the device illustrated in Fig. 3; Fig. 5 is a similar view of a modified form of fitting; Fig. 6 is a similar view of a still further modified form of fitting; and Fig. 7 is an enlarged sectional view taken on the line 7—7 of Fig. 2.

In carrying the invention into practice and for purposes of illustration, a fragmentary portion of a railway car is illustrated, the same including a body 10 which may be suitably mounted upon the truck 11 which may be swiveled to the body as shown at 12, the car being preferably a special construction of sweeper employed for cleaning the tracks 13, such sweeper having two trucks so that the device may be carried at the forward portion of the front truck to proceed in front of the conductor plow, while the sweeper carries the usual revolving brushes, snow plows or other means for cleaning the tracks and roadbed. The truck may be of any preferred construction but as illustrated includes the usual side rails 14 and the end braces 15 while the usual journal boxes 16 are provided for the car axles 11.

17, the wheels 18 of which travel on the tracks 13.

The underground system includes the usual channel castings 19 which form supports for the track rails 13 and which produce the channel 20 by means of a cement or metallic inclosure 21 carried within the U-shaped central portions of the castings. This channel member is extended upwardly and provided with inwardly extending portions 22 producing a channel slot 23, while the opposed portions of the channel producing member at the neck portion 24 of the channel may be braced to the track rails as shown at 25. The channel rails are indicated by the numeral 26, and as illustrated are T-shaped in cross section with the leg portions thereof removably connected to suitable insulator supports 27 to the opposed sides of the channel so that the channel rails lie in spaced parallel relation and are horizontally disposed equidistantly from the center of the channel and the channel slot 23 above the same.

23 Ordinarily the usual conductor plow for transmitting current from the conductor or channel rails 26 is suspended from the car truck at a suitable point about midway of the length of the truck and car, providing the car is a single truck one, and generally at the inner end of each truck if the car is provided with two trucks with four wheels to each. In the present instance, however, the device or apparatus embodies a fitting 28 which is suspended from the extreme outer or forward end of each truck frame in such a manner as to operate in front of the plow and by cleaning the channels and channel rails insure the proper transmission of the current and cleaning of the channel to effect the most efficient operation of the railway system. For this purpose each fitting 28 comprises a suitable rectangular casing which is relatively narrow and long so as to operate through the slot 23 and depend into the channel 20.

Arranged upon the car is a steam generating furnace 29 from which a plurality of steam supply pipes 30 lead, the pipes being capable of independent control as by means of valves 31. These pipes extend through and beneath the floor of the car body, being made flexible for this purpose and provided with suitable couplings 32 at their lower extremities by means of which they may be coupled to the reduced inlets 33, 34 and 35 so as to independently discharge steam therethrough. The connection may be made by the usual threaded couplings or otherwise. The inlets may form a part of a casting 36 producing a head for the fitting and may be separate therefrom or otherwise.

As illustrated, each fitting is in the form of a narrow casting carrying a plurality of incased tubing and the inlet 33 discharges

through a pair of passages 37 and through a corresponding plural number of tubes 38 incased in the casting forming the fitting and communicating with the respective passages so as to discharge the steam through outlet passages 39 and through a forwardly extending nozzle 40 located about midway of the height of the fitting so as to discharge the blast of steam at and between the opposed portions of the casting or channel at the channel slot and thus effectively remove snow, ice and sleet therefrom. While two passages 37 in a corresponding number of tubes or passages 38 are shown, any number may be employed, the advantage of providing a plurality of such passages and tubes being to increase the cross sectional area through which the steam is discharged owing to the restricted width of the channel slot, so that a maximum quantity of steam may be discharged against the parts to be acted upon. The supply and discharge orifices are preferably made of such size as to approximate or equal the combined cross sectional area of the passages communicating therewith so that the least possible resistance will be offered to the discharge of the steam, while through the medium of the valve provided for the supply pipe thereof such discharge may be regulated as desired.

The inlets 34 and 35 each lead to a plurality of passages or tubes 41, preferably four in number, passages 42 in the head 36 communicating with said tubes and forming intermediate deflectors tapering toward the supply end so as to uniformly divide the volume of steam through the various passages and tubes to further avoid resistance. These series of tubes are preferably spaced apart by a wider casting portion 43 so as to give strength and rigidity to the fitting which, in its preferred form, is cast or molded from some tough material or metal such as an alloy of steel or copper. The respective pairs of tubes discharge through passages 44 into separate discharge nozzles 45 and 46, the outlet orifices 47 of which are bent or extended in opposite directions, as is more clearly shown in Fig. 1 of the drawings, so as to direct the steam against the opposed conductors or channel rails 23 for the purpose hereinbefore described. The fittings are preferably supported upon cross beams 48 secured at their extremities to the sides and ends of the truck frame or otherwise mounted thereon, said beams being of circular cross section at their intermediate portions. Movably mounted on these cross beams is a longitudinal support 49, the same being loosely connected at its reduced end portions 49' to sleeves 50 slidably mounted on the cross beams through the instrumentality of studs 50' projecting upwardly from the sleeves and loosely engaging apertures in the longitudinal support 49. Sleeves 51

are engaged on the studs and loosely mounted in the openings at the ends of the longitudinal support, while nuts 52' are mounted on the studs with interposed washers to engage the sleeves while permitting the longitudinal support to move in angular relation to the sleeves as the latter slide in a minute degree upon the beams as the car is turning a curve or due to any other irregularity in the slot. The fitting is preferably secured to the longitudinal support 49 in conjunction with a spaced longitudinal support 53', the connection being made by means of bolts 54', which pass through the fitting and through said spaced longitudinal supports. Owing to the use of the flexible connections 30 and the suspension of the fittings in the manner specified so as to pivot or move in angular relation to the car, and the fact that they are formed of tough malleable material, slight inaccuracies in the walls of the slot will be readily compensated for, assisted by the movement of the truck as the car travels along the track rails. In this manner the proper discharge of the steam to remove the ice, snow and sleet from the opposed walls of the slot of the channel, the channel and the conductors or channel rails, is insured.

In the form of the invention illustrated in Fig. 5 of the drawings the fitting, in lieu of being provided with a plurality of passages and tubes incased in the same, the advantage of which is that the tubes are of such material as to resist the action of acid or other constituents of the steam so that the casting may be made of cheaper and more suitable material, is provided with a rectangular and relatively flat casing or tubing 51 which is embedded in the casting and which alone is designed to discharge through the nozzle 40. In lieu of the tubes 41 open rectangular castings or tubes 52 of relatively flat cross section are provided, the same being also spaced apart a greater distance than the space between the casing 51 and the adjacent casing 52 in order to strengthen the casting at the point due to the extension or location of the discharge nozzles 45 and 46 beneath the nozzle 40 and thus the increased length of the casting at this point.

In the form of the invention illustrated in Fig. 6 of the drawings a rectangular casing 52 is employed in lieu of the tubes 38 and the casing 51, and the same is divided by a partition or wall 54 producing a pair of passages 55 corresponding to the tubes or passages 38 and for use with similar inlet and discharge nozzles, while with the structure shown in Fig. 5 the intermediate walls in said nozzles are omitted. In lieu of the casings 52, casings 56 are provided, the same having dividing or partition walls 57 for the purpose of providing a plurality of

passages 58 corresponding to the bores of the tubes 41 and adapted to discharge the steam in the same manner.

It will thus be seen that I have provided a simple and efficient device for thoroughly removing ice, snow and sleet from the opposed walls of the channel slot, the channel and channel rails of an underground electric railway system or the like which, together with the usual sweepers or plows provided for cleaning the tracks, will permit the continued and uninterrupted operation of a railway system.

Having thus described my invention, what I claim as new and desire to secure by Letters Patent is:—

1. A device for removing snow, ice and sleet from channels and channel rails of underground railways, comprising a fitting having a plurality of passages with independent exhaust nozzles, one of which is adapted to be directed between the channels of such system through the slot thereof and the others of which are adapted to discharge against the conductor rails.

2. A device for removing snow, ice and sleet from channels and channel rails of underground railways, comprising a fitting having a plurality of passages with independent exhaust nozzles, one of which is adapted to be directed between the channels of such system through the slot thereof and the others of which are adapted to discharge against the conductor rails and a source of steam supply for said passages with means to independently control the same.

3. A device of the class described, comprising a fitting having a plurality of series of passages therethrough, independent inlets for each series of passages for the discharge of steam therethrough, one series of passages having a discharge nozzle forming a part of the fitting, located intermediate the ends thereof, and the bottom portion of the fitting being provided with oppositely projecting nozzles communicating with the other series of passages.

4. A device of the class described, embodying a fitting formed of a casting of tough malleable material with incased passages having independent inlets and outlets at the upper and lower ends thereof respectively and castings at said ends, the castings at the upper ends having means for the attachment of pipes thereto and the castings at the lower ends having discharge nozzles.

5. A device for removing ice and the like from the channels and channel rails of underground railway systems, comprising a relatively flat fitting having a plurality of independent passages therethrough with separate discharge nozzles, one nozzle being designed to discharge into the slot of the channel and the other nozzles being de-

signed to discharge into the channel and against the conductor rails therein.

6. A device for removing ice and snow in the manner specified from underground railways having a channel with opposed conductor rails and a slot communicating with said channel, comprising a steam generator carried upon a car or the like, a fitting having independent inlets and outlets, said inlets having communication with the generator for receiving a supply of steam therefrom simultaneously or independently and being adapted to operate in said slot to discharge steam into the slot and channel and against the conductor rails.

7. A device for removing ice and snow in the manner specified from underground railways having a channel with opposed conductor rails and a slot communicating with said channel, comprising a steam generator carried upon a car or the like, a fitting having independent inlets and outlets, said inlets having communication with the generator for receiving a supply of steam therefrom simultaneously or independently and being adapted to operate in said slot to discharge steam into the slot and channel

and against the conductor rails and means to removably and pivotally suspend said fitting from a car truck to operate in front of the usual conductor plow employed for transmitting current from the conductor rails to the car motors.

8. A device of the class described including a fitting formed of tough material and a series of casings vertically through the same forming independent passages, heads at the upper end of the fitting producing inlets, nozzles at the lower ends of said passages, one of said nozzles terminating above the others, means to support the fitting from the truck of a car and a source of steam supply connected to the inlets, said casings and parts with which the steam comes in contact being of acid-resisting material.

In testimony whereof I have signed my name to this specification in the presence of two subscribing witnesses.
